SWIMMING DEVICE

Filed March 11, 1931

UNITED STATES PATENT OFFICE

EDWARD L. BELLMAN, OF ROCKFORD, ILLINOIS

SWIMMING DEVICE

Application filed March 11, 1931. Serial No. 521,707.

My invention relates to swimming devices and has particular reference to a device adapted to be secured to the hands and to the feet of a swimmer to augment the natural surface area utilizable for propelling the swimmer through the water.

I have aimed to provide a swimming blade adapted to be pivotally secured to the hand of the swimmer and to bear against the palm of the hand and forearm when the hand and arm of the swimmer are drawn downward in a power stroke.

Another object of the invention is the provision of a swimming blade arranged to offer but little resistance to the movement of the hand during the return stroke.

A further object of the invention is the provision of a swimming blade which may be secured either to the hands or to the feet of the swimmer.

Another object of the invention is the provision of a device of this character which may be manufactured at a substantially smaller cost than other devices heretofore known.

Other objects and attendant advantages will become apparent to those skilled in the art from the following description and the accompanying drawing in which—

Figure 1 is a side view of the swimming device showing it secured to the hand in the position which it will normally occupy during the power stroke, and, in dotted lines, the position which it will occupy during a portion of the return stroke;

Fig. 2 is a front view of the swimming device showing the fingers of the swimmer in section; and

Fig. 3 is a top view of the device showing the manner in which it may be secured to the foot of the swimmer.

Referring now to the drawing, the numeral 5 designates a blade of desired shape characteristics, the shape shown in the drawing having been shown to be satisfactory for the purpose. The paddle should be formed preferably of light material such as wood or may be made of light metal such as aluminum. If desired, the paddles may be made hollow to hold a quantity of gas

whereby their buoyancy is increased. In this particular instance the paddle has been formed from a series of layers of wood veneer whereby it may be formed of wood in comparatively thin cross-section and yet have sufficient strength to withstand the pressure of the water against it during the power stroke of the swimmer. Spaced leather loops 6 and 7 are secured to the upper edge of the blade 5 by means of rivets 8 and 9 or by any other suitable means. The rivets pass through the blade 5 and secure the ends of the loops 6 and 7 to opposite sides of the blade. These loops may be formed of any strong flexible material such as leather for example.

A leather or similar strap 10 is passed through the loops 6 and 7 and is provided with a buckle 11 at one end and a series of holes 12 cooperable therewith at the other end to form a loop. The length of this loop may be regulated by a buckle 11 and holes 12 to receive the fingers 13 of the hand 14 of the swimmer. While the fingers of the swimmer may be inserted in the loop formed by the strap 10 in a number of different ways, I have found it advantageous for the swimmer to place the center two fingers 15 and 16 of the hand beneath the strap 10 in the area between the two loops 6 and 7 and to place the little and the index fingers within the loop formed by the strap 10, upon the loops 6 and 7. In this manner the blade 5 is firmly secured to the hand of the swimmer, the loops 6 and 7 being allowed to slide on the strap 10 to permit pivotal movement of the blade.

Thus while swimming with the device applied to the hands of the swimmer a blade is secured to each hand in the manner shown in Figs. 1 and 2. The blade 5 is caused to lie back from its pivotal support across the hand 14 and the wrist 19 of the swimmer. As the hand is brought downward in a power stroke the blade 5 will be forced against the palm of the hand and the wrist until the end of the stroke is reached. At this point the swimmer begins the return stroke during which he desires as little resistance to the water as possible. Thus at the beginning

of the return stroke the blade 5 will drop to a position represented by the dotted lines in Fig. 1 to present the edge of the blade to the water during this movement. As the hand and arm gradually change their position in the return stroke the blade 5 will gradually return to the full line position shown in Fig. 1, in which position it will be when the return stroke is finished and the next power stroke begins. Thus the device automatically operates to present the maximum resistance to the water during the power stroke and the minimum resistance thereto during the return stroke. This occurs without any conscious effort on the part of the swimmer.

To secure the blade to the foot 26 of the swimmer a pair of spaced slots 20 and 21 are provided on the end of the blade 5 opposite the loops 6 and 7. These slots are so spaced as to receive a strap 22 which passes through the slots 20 and 21 around the toes of the swimmer, designated generally by 23, and back to the opposite side of the blade, where the ends of the strap are secured together by means of a buckle 24 and openings 25 cooperable therewith. The strap 10 is passed around the leg 27 of the swimmer and drawn tight by means of the buckle 11 as will be apparent. Thus the blade 5 is firmly secured to the foot of the swimmer between the leg 27 and the toes 23. Because of the movement of the feet in swimming it is unnecessary that the blade 5 be movable with respect to the foot, the normal movement of the foot 26 in swimming causing the resistance of the blade 5 to be increased and decreased as desired.

It will be seen that I have provided a highly simplified swimming device which may be employed on either the hands or the feet of the swimmer. When the blades are employed upon the hands of the swimmer the operation thereof is entirely automatic and the blades move with the movement of the hands and arms to present a maximum resistance to the water during the power stroke and a minimum resistance thereto during the return stroke. The blades are quickly and easily attached to the hands or to the feet of the swimmer and when used on the feet serve to augment the effect of the feet as naturally employed in swimming.

The device may be manufactured at very small cost and may be made of wood, rubber, sheet metal, or the like, and may be made to contain gases to increase its buoyancy.

While I have thus described and illustrated a specific embodiment of my invention I am aware that numerous alterations and changes may be made therein without departing from the spirit of the invention and the scope of the appended claims in which—

1. A swimming device comprising in combination a blade of thin rigid material sup-

ported to lie against and be supported by the palm of the hand and the wrist in the power stroke of swimming, and flexible means for pivotally connecting said blade at its forward edge to the hand of the swimmer, to move between an operative position against the palm and wrist and an inoperative position parallel to the movement of the swimmer's hand on the back stroke, whereby said blade will automatically present a maximum resistance to the water during the power stroke and a minimum resistance during the return stroke. 75

2. A swimming device comprising in combination, a blade of rigid material, and a single flexible means on said blade for securing the latter to the hand of a swimmer, whereby said blade may occupy a position against the palm of the hand during the power stroke of the swimmer and move to a position to present a minimum of resistance to the water 85 during the return stroke, without flexing of the hand.

3. A swimming device comprising in combination, a blade of rigid material, spaced loops on one end of said blade, a strap passing through said loops and adapted to receive the fingers of a swimmer to pivotally secure said blade to the hand of a swimmer, to move between an operative position against the palm and wrist and an inoperative position, whereby said blade may present a maximum resistance to the water during the power stroke and move to present a minimum resistance to the water during a return stroke. 90

4. A swimming device adapted for use upon either the hand or foot of a swimmer comprising, a blade of rigid material having a pair of spaced slots near one end, means on the opposite end thereof for pivotally securing said blade to the hand of the swimmer or fixedly securing one end of said blade to the leg of a swimmer, and means in said slots for securing said blade to the foot of the swimmer. 105

In witness of the foregoing I affix my signature. 110

EDWARD L. BELLMAN.
